CUFFED SLEEVE AND METHOD OF
MAKING THE SAME

Shepard S. Saltzman, New York, N. Y., and Carl T. Sullivan, Greenville, S. C., assignors to Sim-
plon Cuff Corporation, New York, N. Y.

Application February 8, 1950, Serial No. 143,008

14 Claims. (Cl. 2—123)

1

This invention relates to a garment construction. More particularly, the invention concerns a combination sleeve and cuff for shirts or the like and a method of making the same.

In making cuffs for shirt sleeves in the manner conventionally known in the art, as many as eleven distinct operations are required, including the successive assembly and stitching of the inner cuff, outer cuff and liner, turning the cuff inside out, top stitching the cuff, forming the button hole, attaching the button, separately gathering the sleeve at one end, and stitching the cuff to the gathered portion of the sleeve, together with intermediate operations such as snapping the sewing thread chain which interconnects successive cuff assemblies and inspection. Accordingly, an object of this invention is to provide an improved cuffed sleeve construction, the manufacture of which permits a substantial reduction in the number of operations in comparison to that required in making conventional cuffed sleeves.

In the manufacture of known cuffed sleeves, the cuffs are made as a separate assembly and thereafter stitched to the sleeves, the strength of attachment of the cuff to the sleeve being dependent upon the skill of the individual operator in forming the attaching seam. As a result, the problem of non-uniformity in workmanship and resultant product frequently arises, particularly in connection with mass produced garments in the lower cost ranges. Therefore, another object of this invention is to provide a cuffed sleeve construction wherein the cuff in part, constitutes an integral portion of the sleeve, thus eliminating the possibility of detachment of the cuff from the sleeve due to faulty seaming operations.

A further object of this invention is to provide a cuffed sleeve construction which includes a welted upper edge on the outer exposed portion of the cuff together with boxed transverse edges at the opposite split ends thereof, said welted and boxed edges lending a novel as well as pleasing, finished appearance to the cuff as a whole.

In forming cuffed sleeves of the conventional type, the joining of the cuff assembly to the sleeve requires a preliminary gathering of the lower end of the sleeve to reduce the transverse cross section thereof to the dimension of the cuff assembly. Such operation, which is manually performed while the cuff is being stitched to the sleeve, requires operators highly skilled in the art. Accordingly, yet another object of this invention is to provide a cuffed sleeve construction wherein a sleeve member is separately pleated along spaced lines to reduce the transverse cross sec-

tion at one end thereof, previous to subsequent operations which cuff the sleeve, the pleating and cuffing operations being performed by operators of ordinary skill, yet producing a cuffed sleeve of more pleasing appearance than has been obtained with conventional cuffed sleeve constructions.

Still another object of this invention is to provide a cuffed sleeve construction comprising a sleeve member including an extended wrist covering portion at one end thereof and a cuff member disposed over and attached to the wrist covering portion of the sleeve member, the sleeve member being formed from a blank proportioned to provide smooth, unwrinkled surfaces at the wrist covering portion thereof.

Yet a further object of this invention is to provide a cuffed sleeve construction and a method of making the same, which involves a reduced number of operations, permits the utilization of operators of ordinary skill, allows the production of garments of uniform workmanship, permits economies in manufacture, results in a cuff of novel and pleasing appearance and which is practical to a high degree in use.

Other objects of this invention will in part be obvious and in part hereinafter pointed out.

The invention accordingly consists in the features of construction, combinations of elements, arrangement of parts and procedural steps, which will be exemplified in the construction herein-after described, and of which the scope of invention will be indicated in the following claims.

In the accompanying drawings, in which is shown illustrative embodiments of the invention;

Fig. 1 is a top plan view of a cuffed sleeve embodying the invention;

Fig. 2 is a bottom plan view thereof;

Fig. 3 is a bottom plan view of the cuffed portion of the sleeve in opened up condition;

Fig. 4 is a top plan view thereof;

Fig. 5 is a bottom plan view similar to that shown in Fig. 3, with one end portion of the cuff member in open, unfolded condition and with parts cut away;

Fig. 6 is a sectional view taken on the line 6—6 of Fig. 4;

Fig. 7 is a sectional view taken on the line 7—7 of Fig. 4;

Fig. 8 is a top plan view of a cuffed sleeve embodying the invention and illustrating a modification thereof;

Fig. 9 is a perspective view of a device for assembling and securing together the elements of the cuffed sleeve embodying the invention.

Referring in detail to the drawings, A designates a combination sleeve and cuff embodying the invention. The same comprises a sleeve member 10 for a shirt or similar garment, which is provided at one end thereof with a cuff generally designated as 11.

The sleeve member 10 is of generally tubular shape, open at the shoulder end 12 and tapering somewhat in transverse cross section to the wrist end 13. The member 10 is formed by seaming together the opposite side edges of a suitably cut fabric blank by a double stitch line B. The member 10 comprises peripheral edges 12a, 13a, at the opposite ends thereof. The member 10 is split longitudinally from edge 13a to a point 14 intermediate the edges 12a, 13a, thus forming opposed, split edges 15, 16. An elongated fabric reinforcing strip 17 is suitably folded and stitched about split edge 15 and may extend from point 14 to a point short of edge 13a. The marginal portion at split edge 16 may be hemmed as at 18, from the point 14 to edge 13a.

It will be noted that the length of the sleeve member 10 between edges 12a and 13a, for a given sleeve size, is greater than that of a conventional sleeve member by an amount equal to the width of a cuff. The member 10 thus includes a wrist covering portion 20 defined by edge 13a and opposite, end edges 21, 22, extending from edge 13a. The edges 21, 22 merge with split edges 15, 16, respectively.

Since the sleeve member 10, when attached to a garment such as a shirt, must be of such transverse cross sectional dimensions as to provide adequate elbow room, the fullness of the member is not sufficiently reduced at the wrist end 13, despite the taper of the member. In order to further reduce the transverse cross section of the member at the wrist end 13, the member is provided with a plurality of longitudinally extending pleats 23, which may be suitably spaced from each other. The pleats 23 extend from edge 13a to points intermediate the edges 12a, 13a. The pleats may be varied in number and their particular disposition, to suit specific sleeve patterns. The pleats may be formed by a pressing operation and if desired, may be stitched down.

The thus formed sleeve member 10 is ready to have the cuff 11 formed thereon. To this end, there is provided a top cuff member 25 in the form of a substantially rectangular strip of fabric, similar to the fabric of sleeve member 10 and which may be die cut to a predetermined pattern. The member 25 comprises a top edge 26, a bottom edge 27 and end edges 28, 29. There is also provided a substantially rectangular liner member 30 of a coarsely woven fabric. The liner 30 has a width corresponding to the width of the desired cuff 11. The liner member comprises a top edge 31, a bottom edge 32 and end edges 33, 34. The liner member may be provided with tab portions 35 projecting laterally from the corners thereof, for the purpose hereinafter appearing.

It is understood that the longitudinal dimension of the liner member 30 is substantially equal to the corresponding dimension of the wrist covering portion 20 of the sleeve member 10. The dimensions of the cuff member 25 are somewhat greater than the corresponding dimensions of the liner member 30, for the reasons hereinafter appearing.

The top cuff member 25 and the liner member 30 are assembled with the pleated sleeve member 10 and secured in predetermined relation to the

wrist covering portion 20 thereof. To this end, there is provided a sewing machine 1 having a pair of suitably spaced needles 2, on the head thereof. Attached to the head of the sewing machine 1, is a device 3 which includes combined guide and edge folding means 4 and guide means 5 disposed beneath means 4. An edge folding device 6 is mounted on the sewing machine, adjacent one of the needles 2.

The liner member 30 is fed into guide means 5 and the cuff member 25 is fed into the combined guide and edge folding means 4. Simultaneously, the sleeve member 10 is presented to the sewing machine 1, with the wrist covering portion thereof opened in flat condition and with the outer surface thereof, in uppermost position. The edge 13a of the member 10 is folded upwardly and inwardly by the device 6, upon operation of the sewing machine 1. Also, the edge folding means 4 folds marginal portions of the edges 26, 27 of the cuff member 25 downwardly and inwardly about edges 31, 32 of the liner member 30, thus forming exposed folded edges 48, 49 on the cuff member 25. The action of folding device 6 produces an exposed folded edge 42 on the wrist covering portion 20 of the sleeve member. The thus assembled cuff member 25 and liner member 30 is brought into contact with the upper face of the wrist covering portion 20 of the sleeve member by the continued operation of machine 1. The device 3 is so disposed that the folded edge 41 of the cuff member 25 projects slightly beyond the folded edge 42 of the wrist covering portion 20. Also, the liner member 30 is so related to the cuff member 25 and to the wrist covering portion 20, that the end edges 33, 34 of the liner member substantially register with the end edges 21, 22, respectively, of the portion 20, while the end edges 28, 29, of the member 25, project beyond the edges 22, 21, respectively of the wrist covering portion 20.

The needles 2 on sewing machine 1 will form parallel stitch lines 43, 44 to secure the cuff member 25 and liner 30 to the portion 20 of sleeve member 10. The stitch line 43 is disposed closely adjacent folded edge 42 of the portion 20. The stitch line 44 is disposed somewhat inwardly of the folded edge 40 on member 25, thus forming a longitudinally extending welted edge 45 on member 25.

The opposite open ends presented by the end edges of the cuff member 25 are finished by boxing the same about the edges 21, 22 of portion 20. To this end, the edge 28 of member 25 is folded inwardly toward edge 22 of portion 20 but short thereof, forming a transverse folded edge 46 and is again folded inwardly to form a transverse, exposed folded edge 47, which is parallel to edge 46. The folded edge 47 will substantially register with edge 22 of the portion 20. The projecting portion at the opposite edge 29 of the member 25 is similarly folded about edge 21 of portion 20 to form an exposed, transversely folded edge 48. The folded or boxed end portions of the cuff member 25 are secured in place by stitch lines 49 which are disposed inwardly of the folded edges 47, 48 and extend transversely of stitch lines 43, 44. The boxing operation may be performed manually or by means of suitable edge folding means in association with stitching means.

The cuff 11 may be completed by providing a button hole 50 disposed inwardly of edge 47 while a button 51 is attached at a point inwardly of edge 48. Thus the split edge portions of the

wrist covering portion 20 and cuff 11, may be detachably attached together, with the finished edges 47, 48 of the cuff in overlapping relation. If desired, the button 51 may be replaced by another button hole 50, to allow the use of links to interengage the split edges of the cuff 11, thus providing French cuffs.

It will be apparent that the cuffed sleeve construction hereinbefore described entails not more than five separate operations including pleating the sleeve member, edge folding and sewing the cuff member and liner to the sleeve member, boxing the ends of the cuff member, forming the button hole and attaching the button. This is in contrast to the eleven operations required in the making of a conventional cuffed sleeve. Also, operators of ordinary skill can produce the cuffed sleeve embodying the invention, whereas, skilled operators must be used in making cuffed sleeves of the conventional type.

With the wrist covering portion 20 integral with the sleeve member 10 and forming the inner cuff member, there is no danger of detachment of the cuff from the sleeve.

The projecting tabs 35 on the liner 30 are disposed between the folded edges 46, 47, 48, of the cuff member 25 at the corners thereof, thus providing added stiffness and resistance to wear at the corners of the cuff 11.

The overall appearance of the cuffed sleeve embodying the invention, is distinctively enhanced by the novel appearance of the welted edge 45 on the cuff member and the boxed construction at the split edges thereof. The pleasing appearance of the pleated portions of the sleeve member adjacent the cuff 11, is in contrast with the irregularly disposed gatherings and bunched effect found in the cuff-sleeve junction of usual sleeve constructions.

In Fig. 8 is shown a cuffed sleeve construction embodying the invention and illustrating a modification thereof. The sleeve construction A' is similar to that previously described except as hereinafter set forth. The construction A' comprises a sleeve member 10' which is provided at the wrist end thereof with a cuff 11 substantially as previously described.

The sleeve member 10' is distinguished from sleeve member 10 by the omission of pleats 23. To this end, the member 10' is formed by seam- ing together the opposed edges of a fabric blank which has been cut in a manner to provide in the seamed blank a curved, inwardly turned edge 60. The edge 60 extends from a point intermediate edges 12, 13, to edge 13. Thus the sleeve member is progressively reduced in transverse section in an amount sufficient to provide a properly dimensioned wrist covering portion without the need for pleating. The cuff 11 comprising member 25 and liner 30 may be directly applied to the smooth upper surface of the un- pleated, wrist covering portion of the sleeve member 10' in the manner previously described, omitting the pleating of the sleeve member. By the use of suitable patterns, the blank for sleeve member 10' may be cut to provide correct taper and dimensioned wrist covering portions. Such a sleeve member not only eliminates an operation but in addition facilitates the cuffing procedure.

If desired, the lining fabric 30 may be used in the form of a continuous strip taken from a roll of fabric rotatably mounted on machine 1, adjacent device 3. In such case, the fabric 30 may be continuously fed into guide 5 while cuff strips

25 are successively fed to the means 4. The longitudinal marginal portions of each of the strips 25 will be folded about the liner portion underlying the same, in the manner previously described. At the same time, sleeve members are successively presented to the machine 1 with the wrist covering portion opened flat. The individual assemblies of cuff strip and liner portion are properly registered with the sleeve members. This is facilitated by properly spacing the successive cuff strips relative to the liner fabric. The assemblies are stitched to the sleeve members, in succession and the successive cuffed sleeves will be interconnected by the continuous liner 30. The cuffed sleeves are thereafter separated by cutting the fabric 30 at appropriate intervals. The projecting ends of the cuff and liner strips are then suitably trimmed to permit the edges to be boxed about the split edges of the sleeve member, as previously described.

This application contains subject matter common to application Ser. No. 62,061, filed November 26, 1948, now abandoned.

It will thus be seen that there is provided a cuffed sleeve for a garment together with methods for making the same, in which the several objects of this invention are achieved and which is well adapted to meet the conditions of practical use.

As various possible embodiments might be made of the above described invention, and as various changes might be made in the embodiments set forth, it is to be understood that all matter herein set forth or shown in the accompanying drawings, is to be interpreted as illustrative and not in a limiting sense.

Having thus described our invention, we claim as new and desire to protect by Letters Patent:

1. A cuffed sleeve construction comprising a tubular fabric sleeve member including a wrist covering portion at one end thereof, said sleeve member being of reduced transverse cross section at the wrist covering portion thereof, said sleeve member being longitudinally split at the wrist covering portion thereof to provide a pair of opposed edges, a fabric facing strip overlying the outer surface of the wrist covering portion of the sleeve member and including an end portion folded about each of the split providing edges thereof, and means for securing said strip to said sleeve member.

2. A sleeve and cuff construction comprising a substantially tubular sleeve member tapering in transverse cross section from one end to the other end thereof, said sleeve member including a wrist covering portion of reduced transverse cross section at one end thereof, said wrist covering portion being split to provide opposed edges, a strip cuff member on the outer surface of the wrist covering portion of the sleeve member extending from one split providing edge to the other split providing edge thereof, said cuff member including folded marginal portions at the opposite longitudinal edges thereof, the wrist covering portion of the sleeve member including a folded marginal edge portion disposed adjacent one of the folded marginal edge portions of said cuff member and means for securing the cuff member to the wrist covering portion of the sleeve member.

3. A sleeve and cuff construction comprising a substantially tubular sleeve member including an integral portion at one end thereof forming an inner cuff member, said inner cuff member being split to the edge thereof, a strip outer cuff mem-

ber on the inner cuff member, said outer cuff member including opposite end portions boxed about the respective split providing edges of the inner cuff member, said outer cuff member including folded marginal edge portions extending normally to the boxed edges thereof, a pair of parallel stitch lines securing the outer cuff member to the inner cuff member, said stitch lines being disposed parallel to and inwardly of the folded edges of the outer cuff member, thereby forming on said outer cuff member a welted inner edge and a hemmed outer edge opposed to said welted edge.

4. A sleeve and cuff construction comprising a substantially tubular sleeve member including an integral portion at one end thereof forming an inner cuff member, said inner cuff member being split to the outer edge thereof, an outer cuff member on the inner cuff member, said outer cuff member extending to the split providing edges of said inner cuff member, said outer cuff member including a folded longitudinal edge portion projecting beyond the outer edge of the inner cuff member and means for securing the inner and outer cuff members together.

5. A sleeve and cuff construction as set out in claim 4 and further including stiffening means disposed between the inner and outer cuff members, said stiffening means including portions for additionally stiffening the inner and outer cuff members at their corner portions adjacent the split providing edges of the inner cuff member.

6. The method of forming a cuffed sleeve comprising providing a sleeve member including a split wrist covering portion at one end thereof, disposing the wrist covering portion in an open flat condition, positioning a strip cuff member over the outer surface of the wrist covering portion of the sleeve member, folding opposite longitudinally extending marginal portions of the cuff member into contact with said sleeve member, and stitching the cuff member to the wrist covering portion of the sleeve member along lines extending parallel to the folded edges of the cuff member.

7. The method of forming a cuffed sleeve comprising providing a tubular fabric sleeve including a split wrist covering portion, assembling a strip of cuff fabric and a strip of liner fabric in superposed relation to each other, folding opposite marginal edge portions of the cuff fabric about opposite edges of the liner fabric, opening the wrist covering portion of the sleeve to a flat condition, placing the assembled strips of cuff and liner fabric over the wrist covering portion of the sleeve with the ends of said assembly extending to the split edges of said wrist covering portion and securing the assembly to the wrist covering portion of the sleeve.

8. The method of forming a cuffed sleeve comprising providing a sleeve member including an extended wrist covering portion at one end thereof, said wrist covering portion being split to the outer edge thereof, providing a liner member and a strip cuff member having a length greater than the length of the wrist covering portion of the sleeve member between the split edges thereof, bringing the cuff and liner members into overlying relation, folding longitudinally marginal edge portions of the cuff member about longitudinal edges of the liner member, opening the wrist covering portion of the sleeve member to a flat condition, positioning the assembled cuff and liner members on the wrist covering portion of the sleeve member with the ends of the cuff mem-

ber projecting beyond the split edges of the wrist covering portion, securing the cuff member to the wrist covering portion, folding the projecting end portions of the cuff member about the split edges of the wrist covering portion and securing the folded portions of the cuff member at the split edges of the wrist covering portion.

9. A cuffed sleeve construction comprising a sleeve member having a wrist covering portion at one end thereof, said wrist covering portion being split to provide a pair of opposed edges, a cuff member covering the outer surface of the wrist covering portion, said cuff member including a folded end portion located at each of the respective split providing edges of said wrist covering portion and means for securing said cuff member to said wrist covering portion.

10. A cuffed sleeve construction as set forth in claim 9 wherein said cuff member includes a pair of folded marginal edge portions extending at right angles to the split providing edges of said wrist covering portion, and said securing means includes a stitch line extending inwardly of one of said folded marginal edge portions to provide a welted edge at said marginal edge portion.

11. A cuffed sleeve construction as set forth in claim 9 wherein said wrist covering portion includes a hemmed edge extending at right angles to the split providing edges thereof, said cuff member comprising folded marginal edge portions extending parallel to the hemmed edge of the wrist covering portion, one of said folded marginal edge portions projecting beyond the hemmed edge of the wrist covering portion and said securing means including a stitch line spaced inwardly of said last mentioned folded marginal edge portion and adjacent the hemmed edge of said wrist covering portion.

12. A cuffed sleeve construction comprising a sleeve member having an integral wrist covering portion at one end thereof, said wrist covering portion including a hemmed edge, and being split to provide edges extending normally of said hemmed edge, a cuff member covering the outer surface of said wrist covering portion, said cuff member including inwardly folded, opposite edge portions extending parallel to said hemmed edge and a folded end portion located at each of the respective split edges of said sleeve member, a plurality of stitch lines extending parallel to the hemmed edge of said sleeve member for securing said cuff member to said sleeve member, a stitch line extending parallel to the split edges of said sleeve member for securing each of the folded end portions of said cuff member and means located adjacent the respective split edges of said sleeve member for detachably securing adjacent portions of the wrist covering portion of said sleeve member at the split edges thereof.

13. The method of forming a cuffed sleeve construction including a sleeve member having an integral wrist covering portion at one end thereof, said wrist covering portion being split to provide opposed edges and a strip cuff member overlying the wrist covering portion of the sleeve member, comprising successively feeding a plurality of sleeve members to a station with the wrist covering portions thereof open and disposed in a flat condition, feeding a cuff member into overlying relation with the wrist covering portion of each sleeve member, folding longitudinally extending opposite marginal edge portions of the cuff member into contact with the wrist covering portion of the sleeve member and stitching each cuff

member to a sleeve member along lines parallel to the folded edges of said cuff member.

14. The method as set forth in claim 13 and further including the steps of folding the opposite ends of each cuff member about the respective split forming edges of the wrist covering portion of a sleeve member and stitching the folded ends of said cuff member.
